UNITED STATES PATENT OFFICE

EDWARD J. BURNS, OF FALL RIVER, MASSACHUSETTS, ASSIGNOR TO SEARS B. CONDIT, OF BOSTON, MASSACHUSETTS

FUSE PLUG OR THE LIKE

Application filed January 25, 1929, Serial No. 335,046. Renewed January 23, 1931.

My invention relates to a fuse plug for electric circuits which prevents over fusing of the circuit by inserting a coin or tin foil into a cut-out or by the use of a fuse of larger 5 amperage than is proper for the circuit.

Very often when a fuse blows and another one is not easily obtainable, a make shift connection, such as tin foil or a coin, is inserted into the socket to close the circuit. Such an 10 expedient, although serviceable for the time being, really defeats the purpose of the fuse plug where the circuit closer is of higher fusibility than the wire in the system since the wire will melt. The melting of a wire in the 15 circuit, such as one passing in close contact to wood, would give rise to fire.

The fuse plugs now found on the market are made in several sizes, that is to say that the fusible element is varied to fuse at different 20 amperages. The conventional fuses are about five in number and range from thirty to ten amperes. It will be seen that in the event a ten ampere fuse should be blown and a twenty-five ampere substituted therefor, that the circuit would lose its safety factor inasmuch as the substituted fuse would have a fusibility above the danger point. By 25 the use of my proposed fuse plug, where the same is made up in forms peculiar to each amperage, it will be impossible to interchange a fuse plug of higher amperage for one of lower amperage and conversely. As will be appreciated, by making the portion of the 30 fuse plug which remains permanently within the socket of different tapers and the recesses of fuse carrying elements of different tapers, each taper corresponding to a certain amperage, that it will be hardly possible to substitute a fuse carrying element of one amperage for that of another.

It is an object of my invention to provide a fuse plug which is simple in structure and reliable in operation.

Another object of my invention is to provide 45 a fuse plug which is fool proof and precludes the possibility of forming a makeshift connection in the socket after the fuse has blown or the use of a fuse of larger amperage.

Still another object of my invention is to 50 provide a two part fuse plug wherein one of

the complementary parts remain permanently attached within the plug socket, the other or removable part containing the fuse element; the component parts being made in varying amperage sizes, each having a different taper 55 so that the fuse carrying members cannot be interchanged.

Other objects and advantages of my invention will be apparent from the detail description which follows.

I attain these objects and advantages by means of the device illustrated in the accompanying drawing wherein:

Figure 1 is a front elevational view of the 65 female fuse carrying member.

Figure 2 is a cross sectional view taken through the two members of the fuse and showing the two members just about ready to be joined together.

Figure 3 is a bottom view of the lower or 70 male member.

Figure 4 is a cross sectional view of a modification wherein the lower member remains unchanged, but the upper member is made wholly of porcelain and having the ferrule 75 member attached thereto by means of projections.

Figure 5 is a perspective view showing the ferrule member which is secured to the female fuse carrying member for the purpose of closing 80 the circuit through the male member.

Similar numerals refer to similar parts throughout the several views.

Referring to the drawing, the fuse plug consists of the complementary members 1 and 2 85 which are hereinafter referred to as the female fuse carrying member and male member respectively. The male member 2 is adapted to be permanently affixed within a cut-out by means of the clips 3 which prevent its withdrawal. The member 2 may be formed of any insulating material, such as porcelain or hard rubber, and is provided with a disc member comprising a center contact 4 which is attached to a rivet member 5. The member 2 is provided with a tapered portion or boss 6 which is part of said member and is formed at the same time that the member is made. The portion of said tapered portion, adjacent its base, is straight and an 95 100

annular groove 7 is provided between said base portion and the remainder of the male member 2, the disc member 4 forming the bottom of said annular groove. The upper member 1, known as the female fuse carrying member, is provided with a metallic cup member which comprises a center contact 8 which has a configuration substantially the same as the tapered portion 6 and is adapted to fit 5 thereon, the base or rim 9 of said cup being adapted to fit within the groove 7 and to contact the plate 4. Surrounding the member 1 is the threaded shell 10 which is shown to be a narrow band to prevent its being slit and carried under the rim 9 for the purpose of providing a makeshift connection. A fuse 11 passes from the shell 10 to the top or closed part of the metallic cup 8. A window 12 is provided as is conventionally done in fuses. 10 15 20 25 30 35 40 45 50 55 60 65 70 75 80 85 90 95 100 105 110 115 120 125 130

Referring to the modification, the change is made in the female fuse carrying member in that instead of providing the metallic cup 8, a ferrule member 13 is provided which has 25 projections 16 which are inserted into openings provided therefor in the porcelain body of the fuse. The fuse carrying member is made to have a tapered recess for the purpose described before. In all other respects the 30 modification is substantially the same as the structure described in connection with Figure 2.

The manner of use of the above described fuse plug is as follows. The lower or male member is first inserted in place by forcing it into the socket. By means of the fins provided on the edge of said member, it is held in place against removal. The upper or female member 1, containing the fusible element, is the only replaceable part of the fuse plug unit and is screwed in place until it hugs the conical portion of the lower member and contact is made. In the event that the fusible element is blown, the entire upper part 40 45 50 55 60 65 70 75 80 85 90 95 100 105 110 115 120 125 130 is removed and a new one substituted. As previously stated, the male and female members may be made up in different sizes with different tapers, each taper being peculiar to the size of the fuse. This may be done by varying the depth of the male member or changing the size of the annular groove and also changing the female fuse carrying member a corresponding amount. By reason of the fact that the socket employing the proposed fuse is not suited to receive a fuse of higher amperage nor is adapted to be closed by a coin or other makeshift, the fire hazard from the fusing of electrical wiring from excess current is eliminated.

All that has been said above in the description of my preferred embodiment is offered by way of illustration and not limitation. I do not wish to be limited to the exact structure of the preferred embodiment shown and described, or to any particular material used

in the construction of parts, or to the design of parts, but desire protection as against any variations in structure which utilize the principle of my invention and fall within the purview of my invention and are within the spirit and scope of the following claims:

The invention having been set forth, what is claimed as new and useful is:—

1. In combination with a cut-out, a fuse plug comprising two complementary members, one of said members being adapted to be permanently inserted within said cut-out and having a tapered portion thereon of insulating material, said member having a circular groove at the base of said tapered portion, a conductor within said groove which is adapted to make contact with the center contact of the cut-out, the other complementary member having a tapered recess therein and means in connection with said recess adapted to fit within said circular groove and electrically contact the conductor within said groove, said second member having a fusible element therein electrically connecting said conductor.

2. In combination with a cut-out, a fuse plug comprising a female fuse carrying member, a male member complementary to said fuse carrying member, said male member being adapted to be permanently inserted within said cut-out, said male member having a tapered portion of insulating material thereon, an annular groove within said male member adjacent the base of said tapered portion, a metallic disc in said groove adapted to contact the center contact of the cut-out, said female fuse carrying member comprising a body of insulating material having a recessed portion therein corresponding to the tapered portion on said male member, a screw shell on the exterior of said fuse carrying member, an annular conductor secured to said body adjacent said recess and protruding below, a fusible element passing from said annular conductor to said screw shell of said female fuse carrying member, said annular conductor being adapted to slide into said annular groove when the fuse carrying member is in position to close the circuit.

3. In combination with a cut-out, a fuse plug comprising two complementary members, one of said members being adapted to be permanently inserted within said cut-out and having a tapered portion thereon of insulating material, said member having a circular groove at the base of said tapered portion, a conductor within said groove which is adapted to make contact with the center contact of the cut-out, the other complementary member having a tapered recess therein, a metallic cup like member within said recess having a skirt portion adapted to fit within said circular groove and electrically contact the conductor within said groove,

said second member having a fusible element therein.

4. In combination with a cut-out, a fuse plug comprising a female fuse carrying member, a male member complementary to said fuse carrying member, said male member being adapted to be permanently inserted within said cut-out, said male member having a tapered portion of insulating material thereon, an annular groove within said male member adjacent the base of said tapered portion, a metallic disc in said groove adapted to contact the center contact of the cut-out, said female fuse carrying member comprising a body of insulating material having a recessed portion therein corresponding to the tapered portion on said male member, a screw shell on the exterior of said fuse carrying member, a metallic cup like member within said recess having a skirt portion protruding below, said skirt portion being adapted to slide into said annular groove when the fuse carrying member is in position to close the circuit.

5. In combination with a cut-out, a fuse plug comprising two complementary insulating members, one of said members having a raised portion thereon, the other of said complementary members having a fusible element, a recess corresponding to said raised portion and a screw threaded shell which is connected with said fusible element and screws into said cut-out, a conductor adjacent the base of said raised portion, and a conductor means in combination with the recess for contacting said conductor, said fusible element being connected with said conductor means.

6. A cut-out comprising a contact, an insulating member overlying said contact and having a passage leading thereto and a raised portion, and a fuse-carrying member having a recess which receives said raised portion and a contact which projects beyond said member and enters said passage and engages said aforesaid contact.

7. A cut-out comprising a contact, an insulating member which extends above said contact and has a passage leading thereto and an insulating raised portion, and an insulating fuse-carrying member having a recess which receives said raised portion and a tubular center contact which projects beyond the end of said member and enters said passage and surrounds said raised portion and engages said contact, a fusible element in said fuse casing member connected with said tubular shell surrounding and carried by said fuse-carrying member and connected with said fusible element.

8. A cut-out comprising a contact, an insulating member which extends above said contact and has a passage leading thereto and a raised portion, and an insulating fuse-carrying member having a recess which re-

ceives said raised portion and a projecting center contact which enters said passage and a screw-threaded annular shell which surrounds said fuse carrying member, and a fusible element connected between said shell and center contact.

9. A cut-out comprising a contact, an insulating member which overlies and carries said contact and has a passage leading thereto and a raised portion, and a fuse-carrying member having a recess which receives said raised portion and a contact which projects beyond said member and which enters said passage and engages said first-named contact.

10. A cut-out as defined in claim 9, wherein in said passage is annular and the contact of said fuse-carrying member also is annular and encloses both said recess and said raised portion, and a screw-threaded shell surrounding and carried by said fuse-carrying member and constituting a terminal thereof.

11. A fuse plug comprising a fuse-carrying member and a separate insulating member, said insulating member having an annular passage leading from its top face and a center contact at the bottom of said passage having a part that is exposed at the bottom of said insulating member, said fuse-carrying member having an annular center contact that projects beyond its end and enters said passage of said insulating member and engages said center contact thereof.

12. A fuse plug as defined in claim 11 wherein said passage is annular and said insulating member has a raised portion located within the area of said passage, said fuse-carrying member having a recess which receives said raised portion, and said center contact of said fuse-carrying member being annular and enclosing both said recess and said raised portion, and a screw threaded shell surrounding and carried by said fuse-carrying member and constituting a terminal thereof.

13. A fuse plug as defined in claim 11 wherein an insulating boss is seated upon the center contact of said insulating member in said passage and upstands thereabove, and said fuse-carrying member has a recess which receives said boss, said center contact of said fuse-carrying member being annular and enclosing said boss and recess.

14. A cut-out comprising a contact, an insulating member overlying said contact and having an annular passage leading thereto and a fuse-carrying member having a tubular center contact which projects beyond an end of said fuse-carrying member and which fits snugly in said passage and engages said contact.

Signed at Fall River, in the county of Bristol, State of Massachusetts, this twenty-fourth day of January, 1929.
